UNITED STATES PATENT OFFICE.

FLETCHER WILMER YONGE, OF TAMPA, FLORIDA.

SIGNALING APPARATUS FOR MOTOR-CARS.

1,194,920.

Specification of Letters Patent. Patented Aug. 15, 1916.

Application filed November 11, 1914. Serial No. 871,552.

To all whom it may concern:

Be it known that I, FLETCHER W. YONGE, a citizen of the United States, residing at Tampa, in the county of Hillsborough and State of Florida, have invented new and useful Improvements in Signaling Apparatus for Motor-Cars, of which the following is a specification.

This invention relates to signaling apparatus for motor cars, the broad object of the invention being to produce simple, reliable and effective apparatus for visually indicating to a following machine the movements of the machine ahead, the signaling apparatus being designed to convey information as to whether the machine in advance is about to stop or go forward or turn to the right or left, the display of the signals being accompanied by the sounding of an alarm which will more effectively draw the attention of the operator of the following car to the visual signals displayed.

A further object of the invention is to provide in connection with an oscillatory signaling disk, and a plurality of signaling lamps, a signal controlling element so associated with the said disk, lamps and alarm that it will simultaneously operate the signaling lamps and alarm electrically and also mechanically operate the oscillatory disk.

A further object of the invention is to provide a special arrangement of electrical contacts or terminals in such relation to the switch lever of the controller that the operator may either simultaneously operate the signal lamps and audible alarm or operate the same independently of each other.

With the above and other objects in view, the invention consists in the novel construction, combination and arrangement of parts, as herein described, illustrated and claimed.

In the accompanying drawing:—Figure 1 is a face view of the indicator of this invention. Fig. 2 is a similar view showing the door thereof swung downwardly to expose the contained signaling lamps. Fig. 3 is a side elevation of the indicator. Fig. 4 is a vertical fore and aft section through the same. Fig. 5 is a section taken at right angles to Fig. 4. Fig. 6 is a side elevation of the controller. Fig. 7 is a view taken from the opposite side of the controller

omitting the cover plate. Fig. 8 is a vertical section through the controller taken to one side of the switch lever. Fig. 9 is a plan view of the controller showing the notched floor plate. Fig. 10 is a detail perspective view of the cover plate detached. Fig. 11 is a diagram of the wiring and electrical connections.

Referring to the drawings A generally designates the casing of the indicator which comprises an upper section B and a lower section C, the upper section B being preferably cylindrical as shown and provided with doors 1 and 2 arranged at the front and rear thereof for giving access to the mechanism contained in the upper section B of the casing.

The lower section of the casing is laterally elongated as shown in Figs. 1 and 2 and is provided with a door 3 containing a number of panels of different colored glass, *a* designating a blue panel, *b* a yellow panel, *c* a green panel and *d* a red panel.

e designates a centrally located red panel to produce the ordinary continuously burning red signal required by the law at the rear of every motor car whether moving or standing still. The other panels *a*, *b*, *c* and *d* are adapted to be illuminated by the means hereinafter described for signaling the operator of a following car.

Around each of the panels or groups of panels contained in the door 3 extends a flanged guide 4 which is adapted to receive the different colored panels or glasses the same being slid into the guides or flanges 4 and being retained therein by suitable catches or stops 5. The door 3 is hinged along its bottom edge as shown at 6 to the bottom wall of the main section C of the casing so as to cover in a series of illuminating electric lamps *f*, *g*, *h* and *i* corresponding, respectively with the panels *a*, *b*, *c* and *d*; also a lamp *j* corresponding with the red panel *e* of the door 3.

In the upper section B of the casing a shaft 7 is journaled in suitable bearings 8 and 9, 9 designating a relatively long brass bearing or bushing for said shaft. The shaft 7 extends horizontally and is provided at one extremity thereof with an oscillatory signaling disk designated generally at

D. The disk is divided up in the manner illustrated in Fig. 2 to provide quadrant shaped portions of different colors, 10 designating a red section, 11 a yellow section, 5 12 a green section and 13 a blue section. Upon the red section the letter S is shown represented, said letter standing for the word "stop"; on the yellow section 11 the letter F is represented, standing for the word "forward"; on the green section 12 the letter R is represented, standing for the word "right"; on the blue section 13 the letter L is represented, standing for the word "left". The door 1 is provided with 10 a transparent panel 14 corresponding in size and shape with any one of the different colored sections 10, 11, 12 and 13 of the oscillatory disk D, said panel 14 being therefore of just sufficient size to expose one of 15 the different colored sections and the letter thereon at one time.

The operating means for the oscillatory disk B is best illustrated in Figs. 4 and 5 wherein it will be seen that the shaft 7 has fast thereon a drum 15 around which a flexible cable 16 is wound several times. One extremity of the flexible cable 16 is attached at 17 to a cable retracting coiled spring 18 contained in a spring housing 19 shown as 20 of cylindrical shape the lower end thereof being closed by a cap 20 through which is inserted a tension screw 21 adapted to be held fixed by means of a jam nut 22. The other end portion of the cable 16 passes 25 through a tube 23 which leads toward the controller hereinafter particularly described to an element of which it is connected and by means of which it is operated in the manner which will be hereinafter made clear. 30 The disk D is illuminated by an overhead electric lamp 24 screwed into a socket 25 held by a stationary collar 26 to one end of which is connected a tube 27 through which the wires 28 pass to and from the lamp 24. 35 A combined hood and reflector 29 is secured to the top of the casing A and extends from the lamp 24 to protect the same and reflect the rays of light therefrom downwardly over the exposed portion of the oscillatory 40 disk D. The lamps f, g, h, and i are similarly fastened in place as shown in Fig. 4 and the wires thereof all lead into a tubular conduit 31 to the battery, alarm and controller hereinafter more particularly described. 45 In the bottom of the section A of the casing and leading into the lower section C are nipples 32 and 33 through which the wires just referred to pass from the lower section C into the upper section B of the 50 casing A from which they all pass through the tubular conduit 31 referred to as shown in Fig. 5.

In addition to the features above de-

scribed, the casing A is shown as provided with the socket pieces 34 at opposite sides 65 thereof to enable the same to be fastened upon the usual bracket arms 35. At the bottom the casing is provided with a pendant flange or extension 36 provided with slots 37 to receive the fastening bolts of the 70 usual number plate which is thus adapted to be attached to and supported by the indicator above described.

38 designates an audible alarm shown in the form of a bell attached to any convenient 75 part of the indicator.

The controller comprises a wedge shaped casing designated generally at E said casing having journaled therein a horizontal rock shaft 39 upon which is mounted a lever 80 40 constituting a switch lever. Extending upwardly from the main body 40 of the lever is an arm 41 upon the upper end of which is a pedal 42 adapted to be operated by the foot of the driver of the car. The top 43 of the 85 controller box is in the form of a plate as shown in Fig. 9, the same being adapted to be set flush into the floor of the machine within easy reach of the operator's foot, said plate 43 being formed with a slot 44 for the lever 40 and said slot being offset at 90 periods to provide notches 45, 46, 47 and 48 into any one of which the upper portion of the lever may move for the purpose of energizing the lamps for the pre-arranged signals, the notch 45 being adapted to hold the lever of the controller when turning to the left as indicated, the notch 46 when the signal points to the right, the notch 47 for the forward position and the notch 48 to indicate that the car is about to stop, the said designating words being shown in their proper order in Fig. 9.

Extending along opposite sides of the main body 40 of the switch lever are contact plates 49 and 50 having binding posts 51 and 52 from which wires lead through an outlet nipple 53 to the carbon of the battery designated at F. Just under the plate 43 and arranged in groups are contact fingers 105 or terminals K and L. Each of these contact plates extends inwardly from a post 54 which as shown in Fig. 8 extends through a terminal board 55 where it has connected thereto the appropriate one of a series of 110 wires 56. All of these wires 56 lead to binding posts 57 on a terminal plate 58 shown as secured to the terminal board 55, the latter being formed with any suitable insulating material. Finally all of the wires lead outwardly through a nipple 59 at the bottom of the controller box to points to be hereinafter referred to. The binding posts and wires, etc., are housed in and concealed by a back cover 60 which is flanged as shown at 61 and 120 formed with slots or notches 62 to receive

screws 64 on the controller blocks, the back cover 60 being held in place by nuts 65 or equivalent fastening devices.

Extending in a generally horizontal plane from the switch lever 40 is a lever arm or link 66 the same being fastened to the lever 40 at 67 and having the adjacent end of the flexible cable 16 attached to the extremity thereof at the point 68. Therefore when the operator moves the switch lever in a forward direction, the arm 66 pulls on the flexible cable 16 and by means of the drum 15 oscillates or turns the signaling disk D in one direction. When he releases the pedal, the spring 18 draws the flexible cable 16 in the opposite direction and turns the signaling disk back to its initial position. In the same movement of the switch lever of the controller, the lever is brought into line with the desired notch 45, 46, 47 or 48 and upon entering said notch it comes in contact with one of the terminal contact fingers K thereby energizing the lamp circuit as will hereinafter appear and displaying the appropriate signal formed by the different colored panels a, b, c and d of the indicator hereinabove described. By a forward pressure on the pedal, the lever 41 pushes the contact plate 49 against the finger L which throws in the alarm circuit, thereby ringing the alarm. Thus the operator may either display the lights or sound the alarm separately, the lateral movement of the lever into one of the notches closing the lamp circuit and a forward movement closing the alarm circuit. Upon reaching the foremost contact finger L the bell or alarm is actuated and when the switch lever is returned to its rearmost position it contacts with the adjacent finger K, displaying the red light i to indicate that the machine is standing still.

The arrangement of the electrical connections is best understood from the diagrammatic view, Fig. 11. When the pedal or switch lever is moved into one of the notches of the plate 43, it makes contact with the adjacent finger K whereupon the current flows through the finger K, the appropriate wire 56 to the terminal plate 58, wire 59 to battery 60 and from battery through another wire 59 to the operating lever 40 back to the contact finger K. The lamp J behind the glass disk e is constantly burning at night and is in a separate circuit (not shown). The lamp circuit is thus closed. To throw in the alarm circuit, the lever 40 is pushed forward until it is in contact with the finger L. Thereupon a portion of the current 60 as shown in the diagram, Fig. 11, passes through the contact finger L, wire 70, alarm 38 and wire 71 to the terminal plate 58 thence through the battery 60 to the operat-

ing lever 40 and contact finger L. The same arrangement of circuits is present with each 65 set of contact fingers shown at K and L in the diagrammatic view, Fig. 11, and also in Fig. 6.

It will of course be understood that in the day time the current may be cut off without interfering with the operation of the oscillatory signaling disk D which will continue under the control of the pedal lever of the controller. Furthermore, if desired, the audible alarm may be left in commission 70 during the day time so that it may be sounded in connection with the use of the signaling disk. It will also be observed that all working parts of the mechanism are housed in and thoroughly protected from the 75 weather and also to avoid the same being tampered with by unauthorized persons. The main advantage of the invention resides in the ability of all of the elements of the signaling apparatus being controlled by a 80 single element shown as consisting of the switch lever of the controller. Furthermore the device is exceedingly compact and will take up very little available space in the 85 machine.

Each of the different colored lights will be flashed in accordance with the appropriate colored panel or section of the oscillatory signaling disk. For example, the green light will appear when the signaling disk is 90 turned so as to present the green surface or section thereof and the blue light will flash or be shown when the blue section of the disk appears before the observation opening. When the machine is proceeding straight 95 ahead, the yellow light will be displayed together with the constantly burning red light. The feature referred to is particularly valuable where the motor car is being followed by an engine as the constantly 100 burning red light alone might be confusing to the engineer who would probably mistake the red light for a danger signal on the railway. When, however, one or the other light is being displayed in conjunction with 105 the red light, the engineer is advised that the signal lights are on a motor car and not on a railway train or associated in any way with the railway signaling system.

What I claim is:—

Signaling apparatus for motor cars, comprising in combination, an oscillatory signaling disk, signaling lamps, an audible alarm, lamp and alarm circuits, a series of contacts in each of said circuits arranged in 110 couples, each couplet including a lamp contact and an alarm contact located in spaced relation to each other, and a manually operable controller mechanically connected with 115 said disk for turning the latter and shiftable to a plurality of positions in each of 120 125

which it lies between the contacts of one couplet, the lamp and alarm contacts being so arranged with regard to the controller that by a limited movement of the latter in any 5 of its several positions the lamp and alarm circuits may be independently operated by the controller.

In testimony whereof I affix my signature in presence of two witnesses.

FLETCHER WILMER YONGE.
